United States Patent Office.

EPHRAIM MARTIN AND SAMUEL M. CHITTENDEN, OF BALDWINSVILLE, NEW YORK,
ASSIGNORS TO DANIEL D. CHITTENDEN, OF SAME PLACE.

Letters Patent No. 99,098, dated January 25, 1870.

IMPROVEMENT IN MILKING-STOOLS.

The Schedule referred to in these Letters Patent and making part of the same.

To all whom it may concern:

Be it known that we, EPHRAIM MARTIN and SAMUEL M. CHITTENDEN, both of Baldwinsville, in the county of Onondaga, and State of New York, have invented certain new and useful Improvements in Milking-Stools; and we do hereby declare that the following is a clear and full description thereof, reference being had to the accompanying drawings, forming a part of these specifications, in which—

Figure 1 is a plan or top view of the stool, with pail-rest in position for use.

Figure 2 is a front or side view of the stool, with pail-rest turned under, which is its proper place when not in use.

Figure 3 is a sectional view of pail-rest.

Similar letters of reference indicate like parts.

A is the seat or bed of the stool.

B is a slat-lever, by which the switch-holder is operated.

C is the staff or standard, to which the switch-holder is attached.

D is the clamping-hook or switch-holder.

E is the pail-rest, on which the pail is set when milking.

F F F are the legs of the stool.

g is a staple near top of staff, which serves to keep the clamping-hook in place.

h is a spiral spring under the narrow end of slat-lever.

The slat-lever B is made of half-inch stuff, in shape as indicated in fig. 1, let into the bed of the stool its full thickness at its wide end, rising with a slant to top of stool-bed at the narrow end; it is attached to the stool by a leather hinge at its wide end.

The clamping-hook D is made of half-inch band-iron, bent at each end in opposite directions, forming a flat hook one inch long. One hook is placed under the narrow end of slat-lever B, and secured by a screw; it then passes up the side of staff C, and is

kept in place by staple, g, the upper hook extending across the top of the staff, as shown in fig. 2.

The clamping-hook is operated by the milkman sitting, in part, on slat-lever B. This draws the hook down, with a few hairs of the cow's tail or switch under it, into a slot in top of staff C, thus holding the switch or tail firmly during the process of milking, as seen in fig. 1.

This prevents the cow from annoying the milker, in her efforts to keep off flies with her switch.

The instant the pressure is removed from the slat-lever, it is thrown up by spiral spring h, elevating the clamping-hook, and releasing the switch or tail of the cow, as seen in fig. 2.

The pail-rest is, in form, as shown in fig. 3; it is attached to the stool by slipping it on to the front leg of the stool, which is made straight, and stands perpendicular; it is secured by a pin through the leg, and is adjustable, to be raised and lowered to suit the convenience of the milker, and turned under the stool out of the way when not in use, as seen in fig. 2. By this means the pail is kept from contact with barn-yard dirt, or the filth of the stall, during the process of milking.

We do not claim, separately, either a switch-clamp or a pail-rest in combination with a milking-stool; but having thus described our invention,

What we claim as new, and desire to secure by Letters Patent, is—

The slat-lever B, in combination with the switch-clamp B C D, and the stool A F, provided with the swinging and vertically-adjustable pail-rest E, all constructed, arranged, and operating substantially as herein described.

EPHRAIM MARTIN.

SAMUEL M. CHITTENDEN.
